CLAIM

What is claimed is the ornamental design for a computing device dock, as shown and described.

DESCRIPTION

FIG. 1 is a front view of a computing device dock; FIG. 2 is a back view of the computing device dock from FIG. 1;

FIG. 3 is a top view of the computing device dock from FIG. 1;

FIG. 4 is a bottom view of the computing device dock from FIG. 1;

FIG. 5 is a right view of the computing device dock from FIG. 1;

FIG. 6 is a left view of the computing device dock from FIG. 1; and

FIG. 7 is a top left perspective view of the computing device dock from FIG. 1.

FIG. 8 is a rear perspective view of a computing device dock; and,

FIG. 9 is another front left perspective view thereof, shown in a use coupled with a computing device.

The broken lines in FIGS. 2, 4, and 8 depict portions of the computing device dock that form no part of the claimed design. The broken lines in FIG. 9 depict environment, these broken lines form no part of the claimed design. The line shading is meant to show contour of represented surfaces and not surface ornamentation.

1 Claim, 9 Drawing Sheets
